UNITED STATES PATENT OFFICE.

EDMUNDO GUERRERO, OF ANTIGUA, GUATEMALA.

HYDRAULIC RAM.

1,098,720.

Specification of Letters Patent.

Patented June 2, 1914.

Application filed June 10, 1913. Serial No. 772,773.

To all whom it may concern:

Be it known that I, EDMUNDO GUERRERO, a citizen of Guatemala, residing at Antigua, in the Province of Sacatepequez and Republic of Guatemala, have invented new and useful Improvements in Hydraulic Rams, of which the following is a specification.

The invention has for an object to improve the mounting of the impetus valve 10 in such devices so that the passage from the impetus valve chamber to the air chamber or the delivery line may be more directly in line with the direction of movement of the water in flowing past the impetus valve and developing the momentum required for the blow to be struck.

Another very important object is to so construct the device that air will be fed to the air chamber through the impetus valve 20 port under the normal operation of the device without requiring separate mechanical parts, and operable in connection with an ordinary form of valve.

A further aim is to improve the construction of valves in such devices.

An additional object is to simplify the removal of the impetus valve.

It has been the common experience in such devices that after the impetus valve has 30 been adjusted to act properly, it soon gets out of adjustment because of wear of parts, or for other reasons, and it is also necessary to stop the operation of the device while a new adjustment is made, which then is rather 35 difficult and apt to be inaccurately made except by skilled artisans.

It is therefore an important aim of my invention to provide a valve adjustment, liable 40 in the minimum degree to variation through wear, to enable the adjustment of the stroke without stopping the action and to permit an accurate adjustment to be maintained without requiring skill in manipulating implements or parts of the machine.

45 It has also frequently happened that when used to elevate water to considerable heights gaskets or packings are very difficult to retain in place, and become loosened and blown out under the combined vibration and pressure exerted.

It is a valuable attainment of my invention that the parts are so constructed as to insure the gaskets remaining in place with a moderate compression.

55 Another object of great importance in

such devices is to enable the renewal of the main valve between the feed and the air chamber without entirely removing the air chamber, or disconnecting the delivery pipe although the latter be connected to the bell portion of the chamber direct, thus permitting simplification of the form of the castings required. 60

A further object is to provide an improved means for accurately centering a puppet 65 valve of the mushroom type.

An additional object attained is an increased durability in the impetus valve and the main valve.

An important end attained is the provision 70 of means for releasing and exposing the main valve within the air-chamber.

Additional objects and advantages will be apparent, some of which will appear from the following description, and from 75 the drawings, representing one possible embodiment of the invention, in which,

Figure 1 is a side view of the device, Fig. 2 is a front view thereof, Fig. 3 is a vertical sectional view, Fig. 4 is a detail view 80 of the impetus valve, Fig. 5 is a section on the line 5—5 of Fig. 3, Fig. 6 is a section on the line 6—6 of Fig. 3, Fig. 7 is a detail of the cross-head, Fig. 8 is a detail of the starting lever, Fig. 9 is a detail of the upper 85 valve guide, Fig. 10 is a detail of the main valve seat, Fig. 11 is a fragmentary detail of the air chamber adjustment.

The ram comprises an air chamber 10 substantially in the form of an inverted bottle 90 having a reduced neck 11 at its lower or receiving end, the neck having a flange 12, whereby it may be mounted upon a supporting portion to be described. A delivery terminal 13 is formed on the air chamber 95 casting in the bilge portion and the fastenings for the chamber permit its adjustment of the supporting portion with the terminal 13 at any of four sides, in order that the feed connections may be made at that 100 side most convenient. The lower face of the flange 12 is provided with a shallow groove 14, in which a gasket may be set, and in which the upper portion of a circular bronze plate 15 may be set upon the 105 gasket, the plate being foraminous and having a headed bolt 16 screwed downwardly thereinto, confining a circular flap valve 17, of ordinary form checked against upward flexure beyond a proper limit by means of 110

a disk 18 thereover confined beneath the head of the bolt and having edge-portions turned up to allow proper opening of the valve. The plate 15 is of such thickness that it may be centrally recessed as at 19, to receive the valve, being on this account somewhat cup-shaped in cross section. It is flattened at opposite sides as at 20, for a purpose to be described.

10 The lower side of the plate 15 is extended some distance below the level of the flange 12, and is engaged in the groove 14' formed concentrically of a similar flange 12' circumscribing the upper end of a duct portion 21, forming a part of the main lower casting A. The duct is branched immediately below the flange 12', having two arms extending downwardly and obliquely from the axis of the air chamber in substantially an ogee shape, the two branches diverging and taking an ovate shape in cross section at their lower part, being joined integrally with a circular impetus valve chamber 22, adjacent respective sides thereof. The chamber has vertical cylindrical walls of suitable height, immediately of which there is the usual annular flange 23 projecting inwardly from the sides of the chamber walls and adapted to focus incoming water against the impetus valve, as will be understood.

15 The top of the chamber is covered by a head portion 24, having the central overflow port 25 therein having thin edges and around which there is an annular conical seat 26 presented downwardly, this port opening between the lower ends of the duct branches, the center of this port being spaced from the axis of the air chamber a distance greater than the radius of the periphery of the flanges 12 and 12', in order that the valve stem 27 will be spaced slightly outward of these flanges. The stem 27 carries the impetus valve 28 located within the chamber 22 and adapted to fit on the seat 26 from below, the stem being supported by a spring 28', when the valve is open, engaged around the stem and resting upon the horizontal arm of a bell crank lever 29, pivoted between suitable ears 30 upon a horizontal plate 31 secured upon suitable lugs 32 formed upon the branches of the duct 21 at a suitable point; and by means of a crank-operated screw 33 engaged through a suitable block 34 carried outwardly of the chamber 22 adjacent the downwardly extending outer arm of the lever 29, the latter may be oscillated to raise and lower the valve stem, to properly limit the stroke. By this means there is a minimum of wear, and the action is facilitated and is more positive. The valve stem 27 is provided with a cap 34', adapted to engage frictionally upon the upper end of the stem, being secured thereto by means of a screw 35, so that removal of nuts is not required to

free the valve, the removal of the screw being much easier, as it is difficult to use wrenches satisfactorily upon the valve stem, or nuts engaged thereon.

20 A suitable inlet connection 36 is formed at one side of the chamber 22, the walls of which are smooth at their lower ends, the chamber opening clear toward the bottom and being closed thereat by means of a bottom plate 37 of circular form, of greater diameter than the chamber 22 and projecting outwardly thereof, the upper surface being provided with an annular groove 38 adapted to register with the bottom of the wall of the chamber 22, and intended to receive a gasket therein for engagement against the lower edge of the wall. The bottom is provided with a central circular recess 39, adapted to receive the bottom stem portion 40, which is a continuation of that 27 before mentioned, the junction of the two parts having a shoulder 41 formed thereon upon which the valve 28 is secured by means of a nut 42 engaged upon an enlarged threaded portion of the stem 27. The valve proper 43 comprises an annular plate set upon the shoulder 41, slightly larger than the base of the valve is to be, and upon this there are superposed a plurality of leather disks 44 decreasing successively in diameter from the bottom upward, and trimmed suitably to prevent the proper conical surface for action upon the valve seat 26. The disks are confined by a washer 45 engaged under the nut 42. This construction in an impetus valve 100 adds remarkably to the life of the face, as compared to prior forms, in which the valve seats upon a flat surface. Where the water is lifted to a great height, the blow upon the valve is quite severe, and the constant hammering flattens out the rubber or leather on a flat seat, separating and disrupting the fibers so that the material supporting the shock becomes useless in a very short while. In my valve, on the contrary, the effect is to hold the leather together, compacting it on each blow so that the leather is held together and its wear greatly lessened, the life of the valve being prolonged to several times that of one for which a flat seat is provided. 110 The lower ends of the branches of the duct 21 are joined to the head 24 at opposite sides of the port 25, and the passages therethrough enter the chamber 22 outwardly of the seat 26, there being formed in the roof of the chamber 22 concentric grooves 24', having slides sloping upwardly from close beside the port. These grooves have special important functions that will be subsequently described.

120 Secured upon the upper side of the bottom 37 within the chamber 22 there are three radially arranged bronze guide blocks 47, secured by suitable screws to the bottom, for radial adjustment. Their inner ends are 130

recessed to engage snugly around the stem portion 40, to allow vertical reciprocation thereof and to hold the stem properly centered. Similar guide blocks 48 are secured 5 upon the upper side of the plate 31 by which the lever 29 is supported. In the operation of the device it will be seen that there is no binding of the stem of the valve as would be the case in ordinary forms where the 10 valve is guided only at one end.

After the blow is delivered by the ram during operation, the opening of the valve serves to allow ingress of a number of small bubbles into the grooves 24 through the port 15 25, the groove serving as a trap to prevent escape of the air and to guide it to the duct branches, which are inclined continuously upwardly to the main valve, through which they are carried by the successive blows of 20 the ram.

Projecting forwardly and downwardly from the side of the chamber 22 there is a leg 49, and legs 50 are attached to the rear of the duct, secured in a manner which will be 25 subsequently described. Three legs are preferably provided, the two rear ones adjusted at the rear of the duct, and the device is preferably supported at such a height that when the bottom 37 is removed from the 30 chamber 22, and the top 34' removed from the valve stem, the valve may be readily drawn downwardly and removed.

Two laterally spaced rearwardly projected ears 51 are formed on the upper part of 35 the duct 21 and the legs are secured respectively to the ears 51, one of the securing means being a bolt or shaft 52 extending between the legs and secured in a suitable manner. Pendent upon the shaft 52 there 40 are links 53', pivoted to the lower ends of which is a lever 54 having a suitable handle for its operation projecting rearwardly, the lever being of the first class and having its inner end suitably disposed for vertical movement close to the axis of the air chamber. A cross head 56 is carried pivotally thereby, the outer ends of which are in alignment with guides 57 formed at the sides of the duct. Secured to suitable lugs 58 formed 45 on the side of the air chamber above the flange 12, there are heavy supporting or lifting bolts 59, engaged diagonally through the lugs and extending downwardly to the flange 12, immediately below which they are 50 turned and extended in a vertical direction slidably through the flange 12' and guides. The lower ends of the bolts are rounded and rest in suitable recesses at the outer ends of the cross head 56, the upper ends of the bolts 55 being tenoned in the lugs, whereby, when the lever 54 is operated after the removal of the clamping bolts, the chamber is lifted sufficiently for the removal and replacement of the main valve as before described. The 60 flanges 12 and 12' when in secured position

are spaced apart some distance, the plate 15 being of a sufficient dimension to secure this, so that very slight movement of the chamber 10 gives sufficient space for clearance of, and access to, the plate. The flanges 70 12 and 12' are suitably apertured for the insertion of clamping bolts in the proper number. There will be a minimum binding of the bolts 59 with the guide portions 57 and the operation of renewal of the main 75 valve or parts may be accomplished with but little effort. The projecting top flange portions of the chamber 22 and the bottom plate 37 are provided with registered apertures through which securing bolts 60 may 80 be engaged.

The starting of a ram of this character is sometimes attended with considerable difficulty, if the valve is closed by the power water before there is proper pressure in the 85 delivery system. The proportions and relation of the valve stem and flanges 12 and 12' are therefore especially calculated to facilitate the application of pressure upon the valve stem; and particularly to enable 90 the use of such an implement as that shown in Fig. 8, which comprises a lever 61 having a lip 62 adapted to be engaged beneath one of the flanges, and also a recess 63 adapted to receive the cap 34' therein, being of such 95 length as to be readily operated manually to depress the valve against the maximum water pressure.

It is apparent that notwithstanding the improvements in function attained by the 100 invention, it is nevertheless constructed of few parts, simple to manufacture, whereby its cost is minimized.

The renewal of the wearing surfaces of the valve 28 may be readily accomplished under the construction provided, and it may be noted that in order to secure the nut 42 in place it is provided with a series of radial apertures, and the threaded portion of the stem has a longitudinal groove 42' therein, 105 by which arrangement a cotter pin 64 may be engaged through one aperture with its extremity in the groove, to hold the nut against casual loosening. The screw 33 may be fitted with a detachable revoluble crank 110 thereon, and secured by a screw 65, the weight of which when pendant holds the screw against change of adjustment; and by means of the screw 65, whenever the valve is adjusted the crank may be disposed 115 in pendant position to hold the device as set.

It is to be observed that the construction enables the obtainance of an automatic air feed directly from the impetus valve port 125 or waste opening, and yet enables the use of a vertically disposed valve which is best adapted for accurate feeding and properly balanced movement with a simple construction. The quantity of air supplied is quite 130

abundant, entering on each reaction and being forced by the consecutive impacts into the air chamber together with the water. If the quantity of air becomes excessive, it is 5 simply forced into the delivery line as soon as the level of water in the air chamber becomes lower than the delivery terminal 13.

The pump is especially designed for lifting water to great elevations, and it will be 10 seen that all of the parts are of such design as to best meet such requirements. It is of course understood that the walls of the air chamber and other parts sustaining stress of the water pressure are of sufficient thickness to sustain the maximum pressure to 15 which they are liable.

In order to lessen the pressure necessary to form a water-tight joint between the several castings the grooves for the gaskets 20 may have a medial smaller groove, and those parts engaging in the larger grooves may have a corresponding rib, as shown at 66 in Fig. 11. By this construction the packing material is heavily compressed with but 25 little strain on the clamping bolts, as will be understood. The grooves 24' may be slightly deepened adjacent the lower ends of the arms of the duct 21 so that they will slope continuously upward theretoward, facilitating the movement of air into the duct. 30

What is claimed:

1. In a ram, an impetus valve chamber having a circular waste port in its top part, a circumscribing groove there around with- 35 in the chamber, an air chamber located above the groove in communication with the delivery line of the ram and duct means leading continuously upward from the groove to the air-chamber.

40 2. In a ram, an impetus valve chamber having a circular waste port in its top part, recesses formed closely adjacent the port and having sides upwardly inclined away from the port, an air chamber above the recesses in communication with the delivery 45 line of the ram and duct means leading continuously upward from the recess to the air-chamber.

3. A ram, comprising an impetus chamber 50 member having an upwardly opening port, an impetus valve therefor, integral duct portions extending upwardly from each side of the port being curved laterally in a common direction and inclined upwardly, an air 55 chamber member carried at the upper end thereof in communication with the ducts, the upper parts of the ducts and elements carried thereby being spaced from the axis of the valve, said valve having a stem projecting upward above the lower portions of the ducts, and a check valve between the impetus chamber and air chamber.

60 4. In a ram, an impetus chamber having duct portions leading therefrom, terminating in a ported flange portion, an air cham-

ber thereover having a corresponding flange portion opposed to that first named and adapted to be bolted thereto, a ported valve plate secured between said flanges, a puppet valve carried by the plate opening toward the chamber, securing bolts engaged between the flanges to hold the air chamber in operative position and to secure the said plate, a lever pivoted separately from the air chamber casting, a vertically slid able member carried by the lever for operation thereby, and connected to the air chamber for lifting thereof at times to clear the valve plate, whereby the latter may be removed. 70

5. In a ram, an impetus chamber having a duct portions leading therefrom and terminating in a ported air chamber support, an air chamber thereover having an inlet registering with the port of the support, a valve carrying member removably engaged between the air chamber and support, a puppet valve contained therein opening toward the chamber, means to clamp the valve carrying member between the base of the chamber and the support, a lifting member secured to the chamber and engaged slidably in the support for vertical movement, pendent links carried by the support, a lever intermediately pivoted on the lower ends of the links, and having a major operating arm projected outwardly from the support, and pivotal connections between the minor arm of the lever and said lifting member for lifting the chamber at times and clearance of said valve carrying member for lateral removal. 80

6. A stroke adjusting means for impetus valves comprising a support, a reciprocating valve stem, a lever on the support having an arm embracing the stem, a head on the stem, a spring on the arm adapted to engage the head to check the valve stem in opening movement and means to adjust the lever in various positions to vary the limit of opening movement of the valve. 85 90 95 100

7. In a ram of the class described, an air chamber element having a port opening outwardly, a coaxial reciprocating valve adapted to seat inwardly thereof and having stem portions projecting inwardly and outwardly, circumscribing stationary plate portions adjacent the inner and outer stem portions, radially arranged blocks radially slid able on the plates and having recessed end portions adapted to coengage the respective stem portions for guidance thereof, and means to secure the blocks in adjusted positions. 105 110 115 120

8. A ram comprising an impetus valve chamber casting, a top portion thereon having a concentric port, a valve seat on the inner side of the port therearound, a valve adapted to seat therein having a stem projected outwardly from the port, guide and stroke limiting means engaged with the 125 130

stem above the chamber, duct elements carried by the top of the chamber and having communication with the chamber laterally of said port, the duct elements being inclined laterally and upwardly, away from the axis of the port and terminating in a single flanged member, an air chamber having a flanged inlet portion adapted for engagement with the said flanged member, a main valve for the air chamber inlet, and

supply and delivery connections for the impetus valve and air chambers respectively.

In testimony whereof I have hereunto set my hand in presence of two subscribing witnesses.

EDMUNDO GUERRERO.
